CURTAIN ROD

Filed Dec. 13, 1923

FIG. 1.

FIG. 2.

FIG. 3.

FIG. 4.

FIG. 5.

FIG. 6

A diagram of a bridge structure with numbered points. Point 3 is at the left end, point 2 is the second support from the left, point 1 is the third support from the left, point 5 is the fourth support from the left, point 4 is the fifth support from the left, and point 6 is at the right end. The bridge has two towers and a central arch.

UNITED STATES PATENT OFFICE.

ETHEL M. KRIST, OF SACRAMENTO, CALIFORNIA.

CURTAIN ROD.

Application filed December 13, 1923. Serial No. 680,408.

This invention relates to certain new and useful improvements in curtain rods and particularly to the type for suspending curtains or draperies forwardly of window openings.

One of the objects of the invention is to provide a curtain rod of an adjustable type wherein pairs of slidably associated rods arranged in horizontally spaced relation are adapted to support curtains or draperies, one curtain or drapery forwardly of the other to produce novel decorating effect.

Another object of the invention is to provide a curtain rod wherein mounting brackets support the outer ends of a pair of extensible curtain rods with one of the extensible rods projecting from one bracket to the other while the outwardly positioned pair of extensible rods are supported at adjacent inner ends by bracket arms associated with the longer curtain rod.

With the above and other objects in view that will become apparent as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a top plan view of a curtain rod constructed in accordance with the present invention, the same being illustrated as operatively mounted upon a window frame,

Figure 2 is an end elevational view of the curtain rod and its support in mounted position,

Figure 3 is a fragmentary top plan view of the curtain rod,

Figure 4 is a cross-sectional view of the curtain rod taken on a line adjacent one end thereof,

Figure 5 is a detail sectional view showing the arm connection between two curtain rod sections,

Figure 6 is a detail sectional view taken on line VI—VI of Fig. 5, and

Figure 7 is a side elevational view of the mounting bracket for the curtain rod.

Referring more in detail to the accompanying drawing, there is illustrated a curtain rod mounted upon the window frame 1 and supported by bracket rods 2 having a pointed mounting end 3 and a knob head 4,

a pair of spaced right-angularly extending pins 5 extending from the bracket rod 2 at points intermediate the ends thereof as clearly shown in Fig. 7.

60

The curtain rod includes a pair of tubular telescoping sections 6 and 7 having transverse openings 8 adjacent the outer ends thereof to be received on the perpendicular pin 5 adjacent the mounting end 3 of the bracket rod, the telescoping rod sections 6 and 7 accommodating the mounting of the curtain pole upon window frames of different widths.

65

Outwardly positioned curtain rods, each arranged adjacent the rod sections 6 and 7 and spaced at their inner adjacent ends are formed of tubular telescoping sections 9 and 10, each section 10 adjacent the outer end thereof being provided with a transverse opening 11 to receive the outer pin 5 upon the bracket rod 2 while an ornamental head 12 is carried by the extreme outer end of each outer rod section 10 as shown in Fig. 1.

70

The support for the inner end of the outer curtain rod includes an arm 13 having an opening therethrough adjacent one end that slidably and frictionally receives the adjacent portion of the inner rod sections 6 or 7, the outer end of the arm 13 being provided with an opening to receive and support the inner end of the outer rod section 9 as illustrated in Figs. 5 and 6. The frictional engagement between the rod sections 6 or 7 and the arm 13 is sufficient to over-

75

come the weight of draperies on the rod section 9 with the arm 13 retained in a horizontal position. The inner end of the rod section 9 protrudes through the opening in the arm 13 and has a cap 14 threaded thereon, a pin 15 extending transversely of the rod section 9 inwardly of the arm 13 cooperating with the cap 14 to provide a rigid mounting for the adjacent inner ends of the inner curtain rod sections.

80

Curtains or draperies 16 and 17 are supported by the curtain rods 6 and 7 and 9—10 at points between the arms 13 and the bracket rod 2, the draperies 16 being preferably longer than the draperies 17 to obtain the desired decorative effects.

85

100

While there is herein shown and described the preferred embodiment of the present invention, it is nevertheless to be understood that minor changes may be made therein without departing from the spirit and scope 110 of the invention as claimed.

105

What is claimed as new is:—

In a device of the class described, a curtain rod adapted to be supported at its ends on brackets, forwardly positioned shorter curtain rods supported at their outer ends on the brackets, supporting arms extending between the inner ends of the forward rods and the first named rod, the inner ends of the shorter rods passing through openings

in the supporting arm, a pin projecting 10 through the shorter rod engaging the outer face of the arm, and a cap mounted on the outer end of the shorter rod engaging the inner face of the arm for anchoring the inner ends of the shorter rod to the supporting arm. 15

In testimony whereof I affix my signature.

ETHEL M. KRIST.
